UNITED STATES PATENT OFFICE.

CHARLES H. SHEPARD, OF BROOKLYN, NEW YORK, ASSIGNOR TO WYCKOFF, SEAMANS & BENEDICT, OF ILLION, NEW YORK, A CORPORATION OF NEW YORK.

TYPE-WRITING MACHINE.

1,032,087.

Specification of Letters Patent. Patented July 9, 1912.

Application filed October 18, 1904. Serial No. 228,985.

To all whom it may concern:

Be it known that I, CHARLES H. SHEPARD, citizen of the United States, and resident of the borough of Brooklyn, in the county of 5 Kings and State of New York, have invented certain new and useful Improvements in Type-Writing Machines, of which the following is a specification.

My invention relates to typewriting machines and it has for its object to provide 10 an improved escapement mechanism.

My invention consists in certain features of construction and combinations and arrangements of parts which will be hereinafter fully set forth and particularly 15 pointed out in the claims.

In the accompanying drawings, Figure 1 is a front to rear sectional view of a typewriting machine having my invention applied thereto; Fig. 2 is a rear elevation of 20 my escapement mechanism; Fig. 3 is a view of said mechanism as seen from the right in Fig. 2, the parts being shown in the position they occupy at the end of the down 25 stroke of a key; Fig. 4 is a view similar to Fig. 3 but showing the parts in normal position; Fig. 5 is a view showing the escapement wheel in elevation and in plan; Fig. 6 is a top plan view showing the parts in 30 the position shown in Fig. 3; Fig. 7 is a similar view showing the parts in normal position; and Fig. 8 is a detail view illustrating a preferred form of one of the parts.

My invention is applicable to typewriting 35 machines generally and also to other machines in which a step-by-step escapement mechanism is used.

In the present instance I have illustrated my invention as applied to a Remington 40 typewriter. The main frame of this machine comprises a base portion 1 from which rise posts 2, which support a type ring 3. The keys 4 are mounted on key levers 5, which are pivoted at their rear ends and 45 which are connected by links 6 with type bars 7 in a manner well-known in the art. A universal bar 8 lies beneath the system of key levers, being suspended by links 9, which are connected at their upper ends 50 with spreading arms 10, which are fixed to and form parts of a lever arm 11, which projects toward the front of the machine from a rock shaft 12, having an arm 13 projecting upward therefrom and having 55 the feed dogs mounted thereon. This is the

well-known dog rocker of the Remington machine. So far as my invention is concerned, the dogs might be mounted on any to and fro moving part and the word "rocker," as used in the claims, is to be 60 understood as referring to any such part having the feed dogs mounted thereon. The rocker is rocked forward by the universal bar and is rocked backward by a spring 65 14 (Fig. 2) which is coiled about the shaft 12 and which is connected at one end to said shaft and at the other end to a fixed portion of the machine. The motion of the rocker under the impulse of this spring is 70 adjustably limited by a set screw 15, which is threaded through the arm 11 and engages a portion of a bracket 16 on which the dog rocker is pivoted. Motion of the rocker in the other direction is adjustably limited by a set screw 17, which is threaded 75 through the arm 13 and the end of which is adapted to engage the bracket 16. The shaft 12 is pivoted at its ends on coned pivot pins 18, which extend through suitable openings in ears 19, which project from 80 the bracket 16, and said pins are secured in position by set screws 20. A platen 21 (Fig. 1) is mounted on a carriage which is adapted to move across the machine and which is drawn across the machine by the usual 85 spring drum. Said carriage has mounted thereon a rack which meshes with a pinion, which is fixed on the forward end of a shaft, which is journaled in the framework and which has mounted thereon an escapement wheel 22. The construction and arrangement of the carriage and connected 90 devices are well-known in the art and it has not been thought necessary to show them in the present case. So far as my invention 95 is concerned, these parts may have any suitable construction, and furthermore, the escapement rack need not be a wheel geared to the carriage but said rack may be in the form of a rack bar mounted on said carriage.

A loose dog or stepping dog 23 is pivoted on the arm 13 of the dog rocker by a pin 24 (Fig. 3). The stepping dog is mounted in a guiding slot in the arm 13, as shown in Figs. 6 and 7, and said dog is normally pressed by a tooth of the escapement wheel 25 into engagement with an adjustable stop which, as here shown, consists of a set screw 105 threaded through the arm 13 and secured in 110

adjusted position by a lock nut 26. When the stepping dog is freed from the escapement rack, as shown in Figs. 3 and 6, it is pressed back into position to engage the next succeeding tooth of the wheel, as shown in Fig. 6, by a flat spring 27 which is secured to the side of the arm 13 by a screw 28 and which presses against a portion of the dog which extends below the pivot pin 24. As shown in Fig. 2 the upper end 29 of said spring is bent away from the arm 13 and extends above the pivot pin 24 and serves to limit the backward motion of the stepping dog when freed from the escapement wheel, thus preventing said dog from moving so far as not to be struck by the next succeeding tooth of the wheel. A holding dog 30 is mounted in a slot in the rear side of the arm 13 in which it is pivoted on a pin 31. A spring 32 secured to the side of the arm 13 by a screw 33, engages a portion of the holding dog and presses it toward the escapement wheel, its motion in this direction being normally limited, as shown in Fig. 4, by the engagement of said dog with a portion of the arm 13.

As best shown in Figs. 6 and 7, the holding dog 30 has a notch 34 in its upper end, and this notch stands in position to receive one of the teeth of the escapement wheel when the rocker is moved toward the front of the machine. The form of this notch is such that one wall thereof holds the escapement wheel against turning and the other wall thereof engaging the face of the escapement wheel arrests the holding dog against further motion into engagement with said wheel, as best shown in Fig. 3. After the holding dog has engaged the escapement wheel, any further forward motion of the rocker results in said holding dog turning about its pivot 31 against the tension of the spring 32. An arm 35 having an inclined face projects from the holding dog into position to be engaged by the stepping dog when said stepping dog is free from the escapement wheel and is thrown back by its spring 27. In the present instance the arm 35 is shown as part of a bracket which is secured to the holding dog by screw 36. When the stepping dog is first freed from the escapement wheel it moves back into engagement with the arm 35, and any further forward motion of the rocker results in said dog slipping over the inclined face of the arm, and being pressed into engagement with said arm by the spring 27. When the key is released and the dog rocker starts on its return motion, the stepping dog engaging the inclined face of the arm 35 presses the holding dog out of engagement with the escapement wheel immediately, the parts on the dog rocker being held in the relative position shown in Fig. 3, by the engagement of the stepping dog with the

arm 35. When the stepping dog is struck by the next succeeding tooth of the escapement wheel it is thrown to its normal position shown in Fig. 7, and is thus disengaged from the arm 35 and the holding dog is then restored to its normal position by its spring 32. 70

In order to prevent the stepping dog from slipping along the surface of the arm 35 during the return motion of the dog rocker, one edge of the stepping dog is concaved as shown at 37 in Figs. 6 and 7. If preferred, the arm 35 may be formed with fine teeth 38 as shown in Fig. 8 to prevent the stepping dog from slipping along said arm. It will be perceived that when the holding dog is arrested in its forward motion by the escapement wheel any further forward motion of the dog rocker results in the stepping dog being moved farther away from the holding dog. It may happen that the distance between these dogs will become greater than the thickness of the escapement wheel, in which case, unless the dog rocker moved back toward its normal position very rapidly, more than one tooth of the escapement wheel might pass between the two dogs before the stepping dog got into position to arrest the wheel. In order to prevent this, a safety dog 39 is rigidly mounted on the arm 13 by means of a screw 40. As will be understood by reference to Figs. 3, 6 and 7 this safety dog stands in such position that after any tooth of the escapement wheel has been released from the holding dog, such tooth will be caught by the safety dog and held by said safety dog until the stepping dog has moved in position to arrest the next succeeding tooth. In the present instance, I have shown both the holding dog and the safety dog beveled. This construction may be employed or not, as desired. 90

The universal bar which operates the dog rocker is in position to be operated by any one of a number of keys; and unless the relation of each of these keys to the universal bar is accurately adjusted, some of said keys will move said universal bar and the dog rocker greater distances than others. In escapements as heretofore constructed, a key that moves the rocker a comparatively short distance will release the escapement wheel earlier in its up stroke than one that moves said rocker a greater distance. It will be perceived that the construction of my escapement mechanism is such that the escapement wheel will be released at substantially the same point on the up stroke of one key as of another, even though the different keys may not be very accurately adjusted with relation to the universal bar, the construction being such that when the dog rocker begins its return motion the holding dog immediately begins to move out of engagement with the escapement wheel whether the dog ro 110

has moved a greater or less distance on its forward stroke. The notch 34 is made shallow, so that every key releases the escapement wheel when such key has moved but a short distance on its up stroke.

The dog rocker may be equipped with the usual arm 41 pivoted thereto at 42 and controlled by a spring 43 for the purpose of locking the escapement wheel against back-

ward rotation when the carriage is moved toward the right or when the carriage release mechanism is operated, and also with the usual arm 44 which forms part of the line-lock mechanism ordinarily employed in the Remington typewriter. In the present construction the stop screw 17 may be dispensed with altogether if desired, as no harm is done in this escapement mechanism by throwing the dog rocker too far forward.

Various changes may be made in the details of construction and arrangement without departing from the gist of my improvements.

It will be perceived that the holding dog and the stepping dog are movable toward and from each other in the direction of the motion of the dog rocker and that means are provided for moving the holding dog out of engagement with the rack at substantially the same point in the upstroke of any key, whether the several keys have been accurately adjusted with reference to the universal bar or not; and also that a safety dog is provided to arrest the rack in case a tooth thereof escapes between the other two dogs. An escapement embodying these features is not claimed in its broadest aspect in this application but is claimed broadly in my prior Patent No. 953,440, dated March 29th, 1910.

What I claim as new and desire to secure by Letters Patent, is:—

1. In escapement mechanism, the combination with a feed rack, of a stepping dog and a holding dog which alternately engage said rack, and means for temporarily causing a direct mechanical connection between said dogs whereby said dogs are caused to start together on the return stroke of the parts.

2. In an escapement mechanism, the combination with the feed rack, of a holding dog mounted for motion transversely of said feed rack, a dog rocker mounted for motion transversely of said feed rack, a stepping dog mounted on said dog rocker, and means operative when said stepping dog is freed from said rack for temporarily mechanically connecting said stepping dog directly with said holding dog, whereby said dogs are caused to start together on the return stroke of the parts.

3. In an escapement mechanism, the combination with the feed rack, of a holding dog movable into and out of engagement with said feed rack, means for limiting the

motion of said holding dog into engagement with said rack, a stepping dog mounted to engage said rack alternately with said holding dog, and means for temporarily mechanically connecting said stepping dog directly with said holding dog when said stepping dog is disengaged from said rack, whereby said dogs are caused to start together on the return stroke of the parts.

4. In escapement mechanism, the combination with an escapement rack, of a dog rocker, a holding dog and a stepping dog, means for arresting said holding dog on the forward stroke of said rocker before said rocker completes said forward stroke, and means for temporarily causing a direct mechanical connection between said dogs to cause said dogs to move together during the first part of the return stroke of said rocker.

5. In an escapement mechanism, the combination with the feed rack, of a dog rocker, a stepping dog and a holding dog coöperating with said rack, means for arresting said holding dog before said rocker has completed its forward stroke, and an arm on said holding dog adapted to be engaged by said stepping dog whereby said holding dog is caused to move in unison with said stepping dog during the first part of the return motion of said rocker.

6. In an escapement mechanism, the combination with the feed rack, of a stepping dog and the holding dog which alternately engage said feed rack, and a toothed member mounted on one of said dogs and adapted to be engaged by the other of said dogs when the stepping dog is freed from the feed rack whereby said stepping dog and said holding dog are caused to start together on the return stroke of the parts.

7. In an escapement mechanism, the combination with the feed rack, of a dog rocker, a holding dog pivotally mounted on said dog rocker, a spring pressing said holding dog toward said feed rack, means for limiting the forward motion of said holding dog, a stepping dog mounted on said dog rocker, and a member mounted on one of said dogs and adapted to be engaged by the other when said stepping dog is freed from the rack whereby said stepping dog and said holding dog are caused to move together during the first part of the return motion of said rocker.

8. In an escapement mechanism, the combination with the feed rack, of a holding dog and a stepping dog which alternately engage said rack, means for limiting the motion of said holding dog into engagement with said feed rack, and an arm mounted on said holding dog and having an inclined face which is engaged by said stepping dog when said stepping dog is freed from the feed rack and whereby said stepping dog and said holding dog are caused to move together

during the first part of the return motion of the parts.

9. In an escapement mechanism, the combination with the feed rack of a stepping dog and a holding dog which alternately engage said rack, means whereby the forward motion of said holding dog is arrested by said feed rack, an arm on one of said dogs having an inclined face which is engaged by the other of said dogs when said stepping dog is freed from the rack whereby said stepping dog and said holding dog are caused to move together during the first part of its return motion.
10. In the escapement mechanism of a typewriting machine, the combination with
15. a feed rack, of a stepping dog and a holding dog mounted to move together and independently one of the other transversely of said feed rack, and means for temporarily 20 causing a direct mechanical connection between said dogs whereby said dogs are caused to start together on the return stroke of the parts.

Signed at the borough of Manhattan, city 25 of New York, in the county of New York, and State of New York, this 17th day of October, A. D. 1904.

CHARLES H. SHEPARD.
